CLARENCE A. DYE, OF TOLEDO, OHIO.

DESIGN FOR A COLLAR-HOLDING DEVICE.

58,220.

Specification for Design.

Patented June 28, 1921.

Application filed January 15, 1921. Serial No. 437,639. Term of patent 14 years.

To all whom it may concern:

Be it known that I, CLARENCE A. DYE, a citizen of the United States of America, residing at Toledo, Lucas county, Ohio, have invented a new, original, and ornamental Design for Collar-Holding Devices, of which the following is a specification, reference being had to the accompanying drawing, forming part thereof.

The figure is a perspective view of a collar holding device, showing my new design.

I claim:

The ornamental design for a collar holding device, as shown.

CLARENCE A. DYE.
